UNITED STATES PATENT OFFICE

GEORGE L. HAWKINS, OF CARROLLTON, MISSOURI

DESIGN FOR A COMBINATION TOILET INSTRUMENT

Application filed May 16, 1933. Serial No. 48,130. Term of patent 14 years.

To all whom it may concern:

Be it known that I, GEORGE L. HAWKINS, a citizen of the United States, residing at Carrollton in the county of Carroll and State of Missouri, have invented a new, original, and ornamental Design for a Combination Toilet Instrument, of which the following is a specification, reference being had to the accompanying drawing, forming part thereof.

Figure 1 is a view in side elevation of a

combination toilet instrument showing my new design.

Figure 2 is an elevational view, looking at the other side thereof.

Figure 3 is a plan view.

Figure 4 is a view in end elevation.

I claim:

The ornamental design for a combination toilet instrument as shown.

GEO. L. HAWKINS.
